(57) **CLAIM**

The ornamental design for a combined bottle and cap, as shown and described.

DESCRIPTION

FIG. 1 is a front view of a combined bottle and cap showing our new design,

FIG. 2 is a rear view thereof;

FIG. 3 is a right side view thereof, the left side view being a mirror image;

FIG. 4 is a top plan view thereof;

FIG. 5 is a bottom plan view thereof, wherein a center of the bottom is concaved for about 1 mm when the combined bottle and cap is seen from a side;

FIG. 6 is a perspective view thereof; and,

FIG. 7 is a perspective view of the combined bottle and cap, wherein the cap is opened.
